SAFETY CONTROL FOR PRESSES

Leo M. Kahn, New York, N. Y.

Application September 29, 1931, Serial No. 565,773

5 Claims. (Cl. 68—9)

This invention relates to improvements in pressing machines for various purposes whose operation may involve danger to the operator. It can be used in any power press, but is more particularly related to garment and laundry presses, on which the moving head of a press must be controlled in such a manner as to positively protect the operator against any hazardous actions on her part.

10 Among the objects of this invention is provision of a simple mechanical device whereby the operator is forced to employ both of her hands for the control of the movable head of such laundry presses. Another object is to provide for the 15 actuation of the machine by foot means, which is releasable by hand operated means. These are other objects of my invention are attained in the construction hereinafter set forth and claimed.

Reference is had to the accompanying drawing 20 in which like numerals and characters refer to corresponding parts throughout the different views.

Figs. 1 and 2 are respective front and side elevations of a laundry press. Fig. 3 is an enlarged 25 top view of part of the safety control device. Figs. 4 and 5 are respective front and side views of a modification of a certain element of the safety control device.

30 My invention is here shown applied to a conventional type of laundry pressing machine consisting of a frame 10, a stationary buck 11, a movable head 12, operated by a toggle joint mechanism 13, which is actuated by a pressure cylinder 14, connected with lever 15 to said mechanism 13.

The cylinder is operated through two valves or 35 main control members 16 and 17 of which the former is employed to release an air pressure which will cause the piston in said cylinder to 40 press head 12 against buck 11.

Valve 17 is employed to release an air pressure to cause a reverse motion of said piston and head 12.

Both valves are fed by a source of power through 5 pipe 18, having therein a stopcock 29 to cut off the power.

A bar 20 fastened to the front part of frame 10 has fulcrumed to both its ends two operating levers 21 and 22. Fastened to their extremes are 0 respective cords or chains 23, 24 passing over respective pulleys 25 and 26 held to frame 10. Cords 23 and 24 are fastened to respective slideable rods 27, 28 located on respective bearing blocks 31, 32 secured to frame 10. To each slide 5 rod 27, 28 is fastened a respective auxiliary con-

trol member 33, 34 located in such a manner that a pedal 30, hinged to bearing blocks 31, 32 is prevented from being operated or pressed in a downward direction.

Springs 35, 36 located on said slide rods between the bearing blocks and the auxiliary control members serve to locate the latter underneath said pedal when the same is not being used.

Extension 37 of pedal 30 carries a spring 38, to retain the pedal in a normal or inoperative position.

When pedal 30 is pressed down, extension 37 will raise valve member 39 for the release of air pressure to lower the head 12.

After said valve member has been raised it will be prevented from assuming its original position 15 through a pawl 40 hinged to frame 10, engaging an extension 41 of valve member 39.

Lever 42 forming a part at pawl 40 is normally located underneath the head of valve member 43 20 of valve 17.

A push rod 44 slidably mounted to frame 10 resting on a push lever 45 and forming a part with lever 42 and pawl 40, serves to release the latter from valve member 39 and thereby eliminate the air pressure on piston 18 and head 12. 25 Pushrod 44 also serves to operate valve 17 to cause piston 18 to remove head 12 from buck 11 to a position as indicated in dotted lines.

The operation of the safety control as illustrated in Figs. 1, 2, and 3 consists in the depression of operating levers 21, 22 by both hands of the operator, to permit the latter to actuate pedal 30. It is obvious that the depression of only one of the operating levers will not release the pedal, so that in this manner the operator is automatically forced to keep her hands away from the buck while the head of the press is descending. When pedal 30 is depressed and valve 16 is caused to permit air pressure to lower head 12 as shown in Fig. 2, the pressure will remain on buck 11 until the operator desires the same to be released. This is done by means of pushrod 44, the function of which has already been described.

In the modification of Figs. 4 and 5 pedal 30 has been eliminated and a foot operated valve 16a is located underneath two auxiliary control members 53, 54 fastened to respective sliderods 57, 58 which are located by respective springs 55, 56. These control members, which overlap each other, are moved to left and right in the manner described, hereinabove for the other construction, and will not permit the operator to depress the valve unless both of her hands have 55

removed the control members to enable her to place her foot between the same, and then cause the machine to operate. If it is desired to keep both head 21 and platform 20, in a raised position while the machine is idle, the air pressure in pipe 19 may be shut off through stopcock 29.

I claim:

1. In a pressing machine, coacting press elements therein, fluid pressure means to actuate said press elements, a valve mechanism to control said fluid pressure means to actuate said press; auxiliary members for obstructing the actuating of said valve mechanism and means requiring the use of both hands for moving said auxiliary obstructing members to permit said valve mechanism to be actuated for controlling the fluid power to effect the closing of said pressing elements, retaining means for holding said valve actuated to keep said press elements in the position after said valve had been actuated, and separate manually operated means for releasing retaining means to allow said pressure means and valve to separate said coacting elements.
2. A press comprising a stationary buck, a movable head, fluid power means for opening and closing the head on the buck, control valves for said power means, a pedal operated mechanism for actuating one of said control valves, a pair of auxiliary control members normally obstructing access to said pedal adapted to be actuated by both hands to permit access to said pedal, to control said valve, for admitting fluid to said fluid power means to effect the closing of the head on the buck, and separate valve controlling means to control the fluid power means to effect the opening of the head from the buck.
3. In a pressing machine, coacting press elements, fluid pressure means to effect pressure between said press elements, a pedal to control

the flow of fluid to said fluid pressure means, auxiliary members for preventing the actuation of said pedal, and control means requiring use of both hands for rendering said auxiliary members ineffective to prevent the actuation of said pedal to permit said pedal to be actuated, means for maintaining the flow of fluid pressure to said fluid pressure means after said pedal had been actuated, and means independent of the two hand control means for controlling the said fluid pressure means to cause the same to separate said press elements.

4. In a pressing machine, coacting press elements, fluid pressure means to effect pressure between said press elements, a pedal to control the flow of fluid to said fluid pressure means, auxiliary members for preventing the actuation of said pedal, and control means requiring use of both hands for rendering said auxiliary members ineffective to prevent the actuation of said pedal to permit said pedal to be actuated, and means independent of the two hand control means for controlling the said fluid pressure means to cause the same to separate said press elements.

5. In a pressing machine, coacting press elements, fluid power means for effecting pressure between and for separating said elements, a pedal, a valve operated by said pedal for admitting fluid to said power means to cause said press elements to effect pressure therebetween, barrier means to inhibit access to said pedal, a pair of auxiliary control members adapted to be actuated by both hands to remove said barrier means to allow access to said pedal to permit actuation thereof, and separate valve means for controlling said power means to separate said press elements.

LEO M. KAHN.
